UNITED STATES PATENT OFFICE.

CHARLES R. LAW, OF MANSFIELD, LOUISIANA.

TONGS.

1,186,919.

Specification of Letters Patent. Patented June 13, 1916.

Application filed August 6, 1915. Serial No. 44,058.

To all whom it may concern:

Be it known that I, CHARLES R. LAW, a citizen of the United States, residing at Mansfield, in the parish of De Soto and State of Louisiana, have invented a new and useful Tongs, of which the following is a specification.

This invention relates to tongs such as chain tongs, etc., one of the objects being to provide tongs having all of the advantages of casing and tool joint tongs, such as used primarily in the construction of oil wells and for like purposes.

A further object is to provide an attachment for ordinary pipe tongs whereby the same tool can be used as casing tongs.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings:—Figure 1 is a side elevation of pipe tongs of ordinary construction having combined therewith an attachment whereby the same can be used as casing tongs. Fig. 2 is a longitudinal section through the attachment and showing the grip block in elevation. Fig. 3 is an end view of the attachment, the grip block being removed. Fig. 4 is a section on line A—B Fig. 2. Fig. 5 is a perspective view of the grip block, a part being shown in section. Fig. 6 is a side elevation of a modified form of tongs.

Referring to the figures by characters of reference 1 designates the head of pipe tongs of any standard form, the same having opposed toothed jaws 2 converging toward one end of the head, while an arm or lever 3 extends from the other end of the head. A chain 4 is secured in the head and is adapted to be connected adjustably to the head in the usual manner. In order to adapt these tongs for use in casing tongs, an attachment such as shown in Figs. 2 to 5 inclusive may be employed. This attachment includes a member in the form of a sleeve 5 adapted to fit snugly over the jaws of the head 1, the in-

terior of the sleeve being tapered toward one end so that the jaws will fit properly therein and the small end of the sleeve being open to permit the chain 4 to extend therethrough. This sleeve is open at both ends and at one side and is provided within the large end portion thereof, with parallel webs 6 extending from the open side to the closed side of the sleeve and forming spaces 7 for the reception of the jaws of the tongs and an intermediate space 8 for the reception of the chain. Inwardly extended flanges 9 are formed along the open side of the sleeve for engaging the jaws and holding the sleeve against lateral displacement relative thereto.

Formed in opposed faces of the sleeve are threaded openings 10 for the reception of set screws 11, these set screws being adapted to bind upon opposite sides of the head 1, thus to fasten the sleeve securely to the head.

Formed in the closed side of the sleeve close to the small end thereof is a transverse groove or channel 12 at the ends of which are provided outstanding ears 13. This channel constitutes a seat for a bearing rib 14 which fits snugly in the channel and is held therein by a pivot screw 15 extending longitudinally through the rib and also through the ears 13. Rib 14 is rounded or substantially semi-cylindrical and is formed upon the back of a grip block 16. This grip block is curved from one end to the other and is provided, on its concave face with transverse teeth or serrations 17, adapted to engage a casing being turned by means of the tongs.

Obviously by loosening the screws 11, the sleeve 5 can be detached readily from the tongs and said tongs used as ordinary pipe tongs.

Instead of providing pipe tongs with an attachment such as described, it is to be understood that, if preferred, and as shown in Fig. 6, the tongs can be provided with the usual toothed jaw 18 at one side of the member or head 19, while at the other side of said member or head may be provided outstanding ears 20 to which a block 21 corresponding with block 16 may be pivotally connected in the manner hereinbefore pointed out. Thus without providing an attachment, the one tool can be used as ordinary pipe tongs and as casing tongs.

Obviously various changes in the arrangement and proportions of the parts can be

made to adapt the attachment herein described for use in connection with tongs of different shapes and sizes, without departing from the spirit of the invention.

5. Importance is attached to the fact that the bearing rib 14 engages the wall of the channel or groove 12 so that said wall thus receives all of the strain exerted through the block 16 and the screw or pin 15 merely operates to hold the parts together.

10. It will be noted that the pivot member 15 is removable so that it is thus possible to remove the grip blocks readily. Consequently, grip blocks of different sizes can be used 15 in connection with the attachment.

If desired the outer walls of the sleeve 5 can be extended so as to be engaged by the chain bolts of the tongs, which construction will be obvious.

20. It will be noted that the block 16 and the chain 4 are extended in the same plane so that when the device is used, the block will grip an object at one point while the chain will grip the object at opposed points and 25 in the same plane.

What is claimed is:—

1. In chain tongs, a member, a chain extending at one end into said member, a toothed grip block pivotally connected to 30 the member and supported therebeyond, said chain and grip block being extended in the same plane.

2. In chain tongs, a head, a member detachably secured to the head, and a toothed grip block pivotally connected to said member.

3. In chain tongs, a head, a member detachably secured to the head, said member having a recess, a grip block, a bearing projection on the block and fitted snugly within 40 the recess, and a pivotal connection between said projection and the member.

4. In chain tongs, a head, a sleeve embracing the head and having an opening for the extension of a chain therethrough, 45 and a toothed grip block pivotally connected to the sleeve.

5. In chain tongs, a head, a chain, a sleeve embracing the head end having an opening for the extension of the tongs chain there- 50 through, means for detachably securing said sleeve to the head, the said sleeve having a recess in one side thereof, a grip block, a bearing projection on the block fitting snugly within the recess, and a pivotal connection 55 between said projection and the sleeve.

6. In chain tongs, a head, a sleeve having separate jaw receiving spaces and mounted on the head, said sleeve having open ends, 60 means within the sleeve for detachably securing the sleeve to the head, and a curved and toothed grip block pivotally connected to the sleeve.

In testimony that I claim the foregoing 65 as my own, I have hereto affixed my signature in the presence of two witnesses.

CHARLES R. LAW.
